J. HARTLEY.
RAILWAY SPIKE.
APPLICATION FILED MAY 3, 1921.

1,425,199.

Patented Aug. 8, 1922.

INVENTOR

James Startley

By W. W. Williamson Atty.

UNITED STATES PATENT OFFICE.

JAMES HARTLEY, OF PHILADELPHIA, PENNSYLVANIA.

RAILWAY SPIKE.

1,425,199.

Specification of Letters Patent. Patented Aug. 8, 1922.

Application filed May 3, 1921. Serial No. 466,416.

To all whom it may concern:

Be it known that I, JAMES HARTLEY, a citizen of the United States, residing at Philadelphia, in the county of Philadelphia and

5 State of Pennsylvania, have invented new and useful Improvements in Railway Spikes, of which the following is a specification.

My invention relates to a new and useful improvement in railway spikes, and has for 10 its object to provide an exceedingly simple and effective device of this character which will have a greater bearing surface upon the base of the rail and one which will have in combination therewith, a wire holder, this 15 being so placed as to assist in holding the spike against displacement.

Another object of the invention is to provide the shanks of the spike with a number of notches which slant outward and upward 20 to permit the spike to be readily placed in the tie, and when in the tie will so embed itself in the wood as to prevent accidental withdrawal.

A still further object of the invention is 25 to produce a spike having a number of shanks parallel with one another, thus giving a firmer hold to the spike when in the tie.

The wire holder may be used for telegraph, telephone or other signal wires or it 30 may be utilized to hold electric wires carrying current to the motors of a train, thus permitting it to be used in place of a third rail.

35 With these ends in view, this invention consists in the details of construction and combination of elements hereinafter set forth and then specifically designated by the claims.

40 In order that those skilled in the art to which this invention appertains, may understand how to make and use the same, I will describe its construction in detail, referring by numerals to the accompanying drawing 45 forming a part of this application, in which:—

Fig. 1, is a side elevation of my improved spike and cooperating wire holder, a portion 50 of the spike in the locality of the wire holder being broken away and sectioned and illustrating their relation to a rail and tie, the latter being shown in dotted lines.

Fig. 2, is a fragmentary side elevation of another formation of wire holder.

Fig. 3, is an enlarged perspective view of 55 the spike.

In carrying out my invention as here embodied, A represents a tie, and B the rail mounted thereon, said rail being held in place by the spikes, one of which is here 60 shown and lettered C. This spike comprises a plurality of shanks D, the lower ends of which are sharpened as at E, and a head F having a rear extension G provided with a hole H. 65

In the shanks D are formed a number of notches I, which may be single or in pairs, each of these notches extending downward and inward, producing relatively sharp edges J, which bite into the wood of the tie 70 and prevent accidental withdrawal.

K represents the wire holder comprising a shank L, which may be plain or in the form of a nail, or have threads M cut thereon to permit the same to be threaded into the 75 tie. With the shank is formed a wrench hold N, in the form of a nut, and with this is formed the integral head O having a plurality of openings P through which pass the wires. This wire holder passes through the 80 hole H in the extension G of the spike, and is insulated from said spike by the insulation Q. The head of the spike is provided with extensions T, the sides of which diverge from the head toward their outer ends as 85 indicated at U.

In practice, the spike is driven into the tie and the wire holder then driven or threaded into the tie through the hole H, said wire holder preventing the raising of 90 the extension portion of the spike, thus preventing the spike from being gradually displaced by vibration.

In Figure 2, I have shown a slightly modified form of wire holder in which a number 95 of arms R are formed integral with the wrench hold thereof, the outer ends of these arms as at S, being adapted to hold the wires, said wires being brazed or in any other suitable manner fastened thereto. 100

When using a wire holder of this description, the upper portion of the wires are unobstructed and may be used in place of the third rail on which a trolley may run.

Of course I do not wish to be limited to the exact details of construction as herein shown as these may be varied within the limits of the appended claim without departing from the spirit of my invention.

Having thus fully described my invention, what I claim as new and useful is:—

In a spike, a plurality of shanks, a head formed integral with said shanks, a plu-

rality of extensions formed with the head, 10 the sides of said extensions diverging from the head toward their outer ends, and an extension formed with the rear portion of the head having a hole for the reception of a wire holder.

In testimony whereof, I have hereunto affixed my signature.

JAMES HARTLEY.
